UNITED STATES PATENT OFFICE.

ALBERT D. CAYWOOD, OF CHICAGO, ILLINOIS.

TRUSS.

1,187,041.

Specification of Letters Patent. Patented June 13, 1916.

Application filed April 12, 1915. Serial No. 20,937.

To all whom it may concern:

Be it known that I, ALBERT D. CAYWOOD, a citizen of the United States, residing at Chicago, in the county of Cook and State of Illinois, have invented a new and useful Improvement in Trusses, of which the following is a specification.

My invention relates particularly to trusses for personal wear; and the primary object of the invention is to provide a simple, strong and durable truss having improved means for adjusting the pad or hernia-retaining member.

The invention is illustrated in its preferred embodiment in the accompanying drawing, in which—

Figure 1 represents a perspective view of a truss constructed in accordance with my invention; Fig. 2, a broken sectional view taken as indicated at line 2 of Fig. 1; Fig. 3, a similar view, showing a different adjustment of the pad; Fig. 4, a vertical sectional view taken approximately as indicated at line 4 of Fig. 1; and Fig. 5, a broken sectional view taken as indicated at line 5 of Fig. 4.

In the preferred embodiment, which is illustrated, the truss comprises a belt A having a rod-form front portion 1; and a pad, or hernia-retainer, B, which is adjustably secured to arms 2 and 3, which, in turn, are adjustably secured on the rod 1.

The belt A is preferably composed of the leather straps 4 and 5, which are adjustably connected at the back; and the rod 1, which has the flattened extremities 6 which are housed in or covered by the front portions of the belt-members 4 and 5. The flattened extremities 6 are suitably curved to correspond with the general curvature of the belt; but the flattened extremities may be bent or readjusted to conform to the hips of the wearer. The rod 1 is preferably of steel and of circular cross-section. The belt 45 is preferably so formed as to pass directly about the hips, the rod or yoke 1 lying transversely in about the same plane as the other portions of the belt. The portions of the members 4 and 5 which contain the flattened extremities of the yoke 1 are curved on quite small radii as indicated at 7, to embrace the sides of the hips. The central portion of the yoke 1 is bowed or struck forwardly, thus providing the obliquely extending por-

tions 8 and the advanced central portion 8^a, 55 the latter extending parallel with the transverse axis of the belt.

The arms 2 and 3 have their upper ends provided with eyes or pivot-lugs 2^a and 3^a, which are mounted on conical surfaces 9 of 60 a split sleeve 10, the ends of the split sleeve being threaded and equipped with nuts 11, by means of which the eye-portions of the arms may be forced on the conical surfaces, said eye-portions, or rings, serving in turn, 65 to cause the two members of the split sleeve to firmly grip the rod. The arms 2 and 3 are of different lengths, and have their lower ends turned each in the direction of the opposite arm to afford pivots 2^b and 3^b, re- 70 spectively.

The pad or hernia-retaining ball B may be of any suitable construction. In the construction illustrated, it comprises an inner dished metal plate 12, an outer dished metal 75 plate 13, padding material 14, and a pad-cover 15, between which and the inner plate 12 the padding material 14 is confined, the marginal portions of the pad-cover being extended between the plates 12 and 13, 80 which serve as pad-cover clamps. The plates 12 and 13 are clamped together by means of a clamping screw 16. The outer or front side of the pad is equipped with a stud or bolt 17, which has swivel connection 85 with the plate 13, and upon which are mounted a pair of clamping plates 18 and 19, which are provided on adjacent sides with grooves which receive the laterally turned extremities 2^b and 3^b of the arms 2 90 and 3. The bolt 17 has a head which lies back of the plate 13, and the shank of the bolt extends freely through an opening 20 in the plate 13, said shank being squared or made angular to engage a corresponding 95 angular aperture in the clamping member 18, the bolt being rotatable or swiveled in the opening 20 of the plate 13. The front portion of the bolt or stud is threaded to receive a nut 21; and there is a small space 100 between the clamping members 18 and 19, so that the clamping members may be caused to tightly clamp the laterally turned pivot members 2^b and 3^b of the arms 2 and 3, in which action the plate 13 of the pad will be 105 at the same time tightly clamped between the head of the bolt and the rear clamping member 18.

The arms 2 and 3 are preferably curved and have their intermediate portions bowed forwardly, so that the upper portion of the pad may partially underlie said arms, as 5 in the adjustment shown in Fig. 2. The arms may be loosened and swung with relation to the rod 1, as will be understood by comparing Fig. 2 with Fig. 3; and thus the arms may be adjusted and firmly secured in 10 any desired position to carry the pad to the proper point and give to the pad the proper tilt with relation to the body. The pad is usually of elongated form, and may be swung or turned about the bolt 17 to enable 15 the pad to be disposed lengthwise in proper relation to the inguinal opening. Thus, the tilt of the pad with relation to the body (to swing the upper edge portion of the pad toward or away from the body) and the 20 longitudinal positioning of the pad can be effected in the manner described; and it is also noted that the split clamping sleeve may be moved longitudinally on the rod 1 to bring the pad to the proper position in 25 side of the pelvic bone or ilium.

The grooves in the clamping members 18 and 19 which receive the pivot 2^b are approximately semicircular, so that there is a confined pivotal relation between the pivot member 2^b and the clamping members 18 and 19. On the other hand, the grooves which accommodate the pivot 3^b are preferably provided with plain opposed surfaces affording some latitude of movement to the 35 pivot member 3^b, when the pad is swung about the pivot 2^b. This will be clearly understood from Fig. 4, and by a comparison of Figs. 2 and 3.

In the drawing, a single pad is shown 40 mounted on one portion 8 of the rod 1. It will be understood that in case of a double rupture, a similar pad may be mounted on the other oblique portion 8 of the rod, the oblique portions of the rod 8 being symmetrically disposed at opposite ends of the 45 central portion 8^a of the rod.

It will be understood that by reason of the fact that the belt passes in one plane about the body, the belt may be very securely adjusted, so that it will properly resist any tendency toward displacement which may be exerted through the pad B and arms 2 and 3. Moreover, the pad and its adjusting arms ordinarily occupy about 55 the same vertical plane as the carrying portion of the yoke 1, so that undue space is not taken up by the arms and the pad.

From the description given, it will be understood that the improved truss is durable, strong, capable of being reliably adjusted, and that the truss may be worn with little discomfort, because of the compactness of arrangement and of the capability of securing proper adjustment.

65 The foregoing description has been given

for clearness of understanding only, and no unnecessary limitation should be understood therefrom, but the appended claims should be construed as broadly as permissible, in view of the prior art.

What I regard as new, and desire to secure by Letters Patent, is—

1. A truss comprising a belt having a rod-form front yoke, a pair of separate rigid arms, adjusting means serving to secure said arms rigidly on said yoke, a pad, and adjusting means carrying said pad and adapted to be rigidly secured to said arms. 75

2. A truss comprising a belt having a rod-form front yoke, a pair of separate rigid arms, adjusting means serving to secure rigidly said arms on said yoke, and a pad tiltably and swivelly and rigidly secured on 80 said arms.

3. A truss comprising a belt having a rod-form front yoke, a pair of arms having laterally turned pivot-ends disposed at different distances from the yoke, an arm-adjusting and securing device mounted on the yoke and carrying said arms and serving to rigidly secure the arms to the yoke in any desired position of adjustment, a pad, and means for fixedly securing said pad in different positions of adjustment on said pivot-ends. 90

4. A truss comprising a belt having a rod-form front yoke, a depending rigid arm adjustably and rigidly mounted on said yoke and provided with a laterally turned pivot at its lower end, a pad mounted on said laterally turned pivot, and means for adjusting said pad in different rigid positions on said laterally turned pivot. 95

5. A truss having a rod-form front yoke, a rigid arm adjustably and rigidly mounted on said yoke, a pad having pivotal connection with said arm, and a second rigid arm adjustably and rigidly mounted on said yoke and having connection with said pad. 105

6. A truss having a rod-form front yoke, a pair of separate rigid arms of different lengths adjustably and rigidly mounted on said yoke, and a pad having adjustable connections with said arms at different distances from said yoke. 110

7. A truss having a rod-form front yoke, a pair of arms adjustably and rigidly mounted on said yoke, said arms being of different lengths and having overlapping laterally turned oppositely directed pivot ends, a pad, and clamping connections securing said pad to said laterally turned pivot ends. 115

8. A truss having a front yoke, a pair of arms adjustably connected with said yoke and equipped at different distances from the yoke with laterally turned pivot members, a pad, and clamping means engaging said laterally turned pivots and having swivel connection with said pad. 125

9. A truss comprising a front yoke, a pair of arms carried thereby and provided at different distances from the yoke with laterally turned pivots, clamping members 5 engaging said pivots, a pad, and a bolt having swivel connection with said pad and serving to secure said clamping members to said laterally turned pivots.

10. A truss having a rod-form front yoke, a clamping sleeve mounted thereon, a pair of arms of different lengths mounted on said clamping sleeve, nuts serving to clamp said arms to the clamping sleeve and to clamp the sleeve to said yoke, and a pad ad-

justably connected with the free ends of said arms. 15

11. A truss having a rod-form front yoke, a clamping sleeve mounted thereon, a pair of arms mounted on said clamping sleeve and provided with laterally turned pivots 20 disposed at different distances from said yoke, a pad, and clamping members connected with said pad and engaging said laterally turned pivots.

ALBERT D. CAYWOOD.
